UNITED STATES PATENT OFFICE

JOHN GODFREY GOURDEAU, OF LAWRENCE, MASSACHUSETTS, ASSIGNOR TO DAVIS & FURBER MACHINE COMPANY, OF NORTH ANDOVER, MASSACHUSETTS, A CORPORATION OF MASSACHUSETTS

HAND CARD

Application filed March 17, 1928. Serial No. 262,578.

This invention relates to a hand card such as is employed for cleaning the card clothing of carding machines and for similar purposes.

- 5 The object of the invention is to provide a simple and durable device of this character in which the card clothing element may readily be removed and replaced when worn or damaged or whenever required.
- 10 The object of the invention is further to provide such a device in which the card clothing element shall be stretched taut and snugly fitted against the face of the base element of the device.
- 15 The object of the invention is further to provide such a device in which the base element is made of metal, and preferably of an aluminum casting, and in which the card clothing element is adjustably secured there-
- 20 to so as to remain taut and snugly fitted against the face of the base element.

Thus the card clothing element may be made and sold as a separate article and supplied to owners of the original base element.

25 These and other objects and features of the invention will appear more fully from the accompanying description and drawings and will be particularly pointed out in the claims.

30 As the hand card is a well known tool or device to those familiar with the carding and similar industries, it will only be necessary to describe and illustrate the novel construction which constitutes the present invention.

35 In the drawings:

Fig. 1 is a view in perspective of a hand card embodying a preferred form of the present invention.

40 Fig. 2 is a view in cross section taken on the line 2—2 of Fig. 1.

Fig. 3 is a detail in cross section taken on the line 3—3 of Fig. 1.

45 Fig. 4 is a bottom plan view of the hand card shown in Fig. 1 with the bent wire teeth omitted.

Fig. 5 is a view in cross section of a card clothing element adapted for embodiment in the hand card of the preceding figures.

50 Fig. 6 is a top plan view of a hand card

embodimenting a different form of the invention.

Fig. 7 is a view in cross section taken on the line 7—7 of Fig. 6.

A hand card essentially comprises a base element, a handle connected to the base by which the device is operated, and a sheet of card clothing secured to the face of the base. The base element is usually made of wood and the card clothing is usually tacked or nailed directly thereto. The backing of the card clothing, being of leather or other flexible material having a different coefficient of expansion to that of the wood, frequently becomes more or less loose as the result of atmospheric or other conditions. Furthermore, the tacks work loose or are pulled out during the use of the hand card, thus not only loosening the connection of the card clothing to the base, but presenting a source of injury or damage to the carding or other machine being cleaned.

In the present invention, one feature resides in making the base of metal, and preferably of an aluminum casting, and another feature resides essentially in detachably connecting the card clothing to the base so that it may be removed and replaced, and in such a way that it may be stretched tightly over the face of the base and all without presenting any points, tacks or fastening means in a position where they would be injured or affected by use of the device. But so far as the latter feature of the invention is concerned, it is not necessary that the base be made of cast metal, or even of metal. It will also be seen that any section of the card clothing may be tightened up independently of the other sections.

A simple and preferred form of the invention is shown in Figs. 1 to 5, inclusive, of the drawings, wherein the base 1 is a cast plate, preferably of aluminum, in order to secure light weight. This plate presents straight, parallel edges, the lower edge 2 being here shown as the plain edge of the plate, with the plate reinforced by a rib 3 at the back having bosses 4 to receive attaching screws. The upper edge 5 is rounded at 6, thus presenting a smooth, round surface over which the card clothing may be

stretched. The upper edge projects at the back of the base and is squared off to present a sharply defined shoulder 7 which faces toward the lower edge.

5 A suitable handle is formed integral with the base and projects centrally from the back thereof away from the lower edge. The integral portion 8 of this handle may be of socket form, as shown, and receive a wooden 10 extension 9 fitted in the socket. The handle 8 presents at its juncture with the back of the base upwardly and outwardly flaring flanges 10 extending toward the upper edge of the base and integral with the base and 15 forming a recess adapted to receive the index finger of the hand of the operator grasping the handle, as indicated in dotted lines in Fig. 4. On the under side of the handle there are formed grooves 11 in position to 20 receive and position the ends of the thumb and a finger such as the second or middle finger of the hand of the operator, as also shown in dotted lines in Fig. 4. This handle also is conveniently provided with a strap 25 12 to encircle the wrist of the operative and thus give a firmer grip on the hand card when in use. To secure this strap in place, the handle on its under side is recessed and formed with a transverse bar 13, around 30 which this strap passes. This bar also serves to reinforce the handle. This construction of recess, grooves and strap enables the operative to have an easy, positive and firm grip on the hand card under all conditions.

35 The card clothing is formed of the usual flexible sheet of leather 14 or other suitable material with the usual bent wire teeth 15 set therein and projecting from the face thereof.

In the construction shown in Figs. 1 to 5, 40 inclusive, the lower edge of the sheet of card clothing is detachably secured directly to the lower edge of the base. As a suitable means for this purpose, a rigid binding strip 16 of metal L-shape in cross section is provided. 45 The lower edge of the sheet of card clothing is bent upwardly around the edge 2 of the back and is clamped between this binding strip and the lower edge of the base. The edge of the card clothing is also bent downwardly so as to extend over the upturned flange of the binding strip 16 as shown at 17. This produces a very firm grip on the edge 50 of the card clothing and with the provision of the rib 3 renders it practically impossible for dirt or lint to work in between the base and the card clothing element. The binding strip 16 and the card clothing are clamped in place by screws 18 having their heads seated 55 in depressions in the strip 16 and projecting up through the card clothing and are threaded into the bosses 4 on the base. The edge of the card clothing is formed with apertures 19 to receive the screws and the sheet 60 of card clothing is countersunk at 20 at these

apertures to receive the depressions in the strip 16.

In this construction the upper or free edge of the sheet of card clothing has detachably secured thereto a rigid binding strip which 70 in the construction illustrated is made of two plates 21, which is L-shaped in cross section, and 22, which is flat, between which the edge of the sheet of card clothing is detachably secured by means of threaded studs 23 75 having their heads 24 flat and resting in depressions in the strip 21. The edge of the card clothing which is thus clamped is likewise formed with apertures 25 countersunk at 80 26 to receive the studs 23 and the depressions in the strip 21, while the terminal edge of the card clothing 14 is bent back at 27 to fit over the edge of the strip 22, thus insuring a firm grip.

When the lower edge of the sheet of card clothing has been clamped to the lower edge of the base, the upper edge is brought up around and over the rounded edge 6 of the base and the sheet of card clothing is then secured at the back of the base. The sheet 90 of card clothing is made of such size that when attached at the lower edge and when the rigid binding strip plates 21 and 22 are attached, the edge of the strip 22 will rest against the shoulder 7 of the base so that as 95 the edge of the card clothing with the binding strip attached is pressed down toward the back of the base, there will be a camming or lever action which stretches the sheet of card clothing taut against the face of the base and this will usually be a sufficient stretching of 100 the card clothing until the hand card has been in use for some time.

Suitable means are provided for securing 105 the upper edge of the sheet of card clothing to the base and also for drawing relatively toward each other the upper and lower edges of the sheet of card clothing. In the construction illustrated, a plurality of longitudinally adjustable connectors are employed. As shown, each of these comprises 110 an internally threaded tube 28 and a threaded stud 29 engaging the tube and passed through a lug 30 projecting integrally from the back of the base. This stud has a slotted head 31 abutting the lug. The tubular member 28 of the connection is also formed to serve as a nut for the stud 23. For this purpose a flattened prolongation 32 is threaded to fit the stud 23. Thus in assembling the parts before the screw 29 and the tube 28 are connected, the tubular member 28 and the stud 23 are screwed together, thus firmly clamping the plates 21 and 22 with the interposed edge of the card clothing 115 backing together.

120 It will be seen, when the parts are assembled as illustrated, that by screwing the studs 29 into the tubes 28, the sheet of card clothing can be further tightened up snugly 130

against the face of the base whenever it becomes loose. The lugs 30 engaging the studs 31 act to prevent any lateral movement of the connectors relatively to the base and consequently any lateral movement between the sheet of card clothing and the base, although in this form of the device such relative lateral movement is chiefly prevented by the connection of the lower edge of the sheet to the lower edge of the base and by flanges 33 formed at the side of the base and extending past the side edges of the card clothing 14. It will also be seen that if atmospheric or other conditions cause the sheet of card clothing to loosen, it can readily be restored to its tight, snug fit by adjustment of these connectors. It will also be seen that as the sheet of card clothing is not tacked or nailed to the base, the wire teeth 15 may be brought close up to the side edges of the base, thus enlarging the effective area of the card clothing without enlarging the area of the base. It will also be seen that when the sheet of card clothing becomes worn or damaged, it may readily be removed from the base and a new sheet of card clothing substituted therefor. It will also be seen that the plurality of adjustable connectors provided enables the sheet of card clothing to be adjusted at any section of its width independently of the other sections, so that if any section becomes slack for any reason whatever, that section may readily be tightened.

35 The construction is such as to produce a very strong and durable hand card. The cast metal base may be made quite thin because it is strengthened and reinforced by the rib 3 and the edge 5 and by the flanges 33. The latter flanges also guard the edges of the card clothing against injury if the operative pounds the hand card to knock off dirt or lint. The tubular members 28 of the connectors are so arranged preferably as to rest against the back of the base, as shown in Fig. 2, which gives additional solidity and prevents any looseness of the parts.

40 The card clothing element will preferably be made in a form exactly to fit the clamping plates and the base and furnished in this form so that all the operative has to do to make a replacement is to remove the old sheet of card clothing, remove the clamping plates, place them in position on the new sheet of card clothing and then attach it to the base in the manner described. The card clothing element will therefore be made as shown particularly in cross section in Fig. 5. It is thus rectangular shaped having the bent wire teeth 15 set therein and projecting from the face throughout its area except at the two longer edges, where there are narrow zones, the one at the upper edge being relatively wider than that at the lower edge, 45 without any teeth. The terminal edges of

the strip at these zones extend as noted at right angles to the sheet and the terminal edge at the lower edge is again bent at right angles, as shown at 17. Thus there is formed at the terminal longer edges of the sheet 70 well defined shoulders which are adapted to fit against the binding strips or plates. It will also be noted that a plurality of apertures extend through the sheet adjacent these longer edges and that these apertures are countersunk at the face of the sheet for the purpose already described of receiving the clamping screws and the depressions in the binding strips or plates. The sheet of card clothing is preferably formed to present this construction by moistening or wetting the zones at the longer edges where there are no teeth and then punching and molding these zonal portions to bring them into the desired shape, as shown in Fig. 5, 75 80 and give the leather a permanent set.

85 The construction illustrated in Figs. 6 and 7 involves the broad features of invention already disclosed. In this construction both the upper and lower edges of the base are formed with the rounded beads 34 to present rounded, smooth edges and the sheet of card clothing 35 is not secured directly to the base at either edge, but both the upper edge 36 and the lower edge 37 are brought around to the back of the base and these edges are directly connected by the longitudinally adjustable connectors so that these edges are drawn toward each other by the connectors to stretch the sheet taut against the face of the base.

90 It will be obvious that the lower edge of the sheet where it passes over to the back of the base is cut away to provide for the handle 38.

95 In this construction both the upper and lower edges are provided with rigid binding strips of the character already described in connection with the upper edge of the sheet shown in Figs. 1 and 2. Each of these binding strips in this construction has secured thereto the internally threaded tubes 39 and these tubes in each case are connected by a right and left-hand threaded stud 40 having near the center a polygonal section 41 to receive a wrench. These studs 40 preferably pass through slotted lugs 42 projecting upwardly from the base so as to prevent any lateral movement of the card clothing sheet with respect to the base.

100 The tubular portions 39 of the connectors in this form are secured to the edge of the backing sheet in the same way as at the upper edge of the sheet shown in Fig. 1, that is to say, they serve as nuts threaded on to the threaded studs 43.

105 While, as pointed out, the card clothing element is formed and molded to present a separate unit for attachment to the binding strips and base, it is nevertheless to be under-

stood that this separate card clothing element may have combined with it the binding strips and be furnished therewith as a repair or replacement part.

5 It will thus be seen that the invention presents a very simple, durable hand card in which the card clothing may readily be removed and replaced and in which under all conditions it may readily be adjusted 10 throughout or at any section of its width and maintained taut and snug against the face of the base, thus producing a very efficient instrument.

Having thus described the invention, what 15 is claimed as new, and desired to be secured by Letters Patent, is:

1. A hand card comprising a base having a convexly curved face with parallel upper and lower edges, a handle projecting from 20 the back of the base, a flexible sheet of card clothing on the face of the base with its lower edge detachably secured to the base and with its upper edge extending around the upper edge of the base to the back thereof, a rigid 25 binding strip secured to the upper edge of the sheet overlying the back of the base, and adjustable connecting means mounted on the back of the base engaging the binding strip and operable to draw the upper edge of the 30 sheet toward the lower edge thereof, thereby to maintain the sheet taut and snugly fitted against the face of the base.

2. A hand card comprising a base having 35 parallel upper and lower edges, a handle projecting from the back of the base, a flexible sheet of card clothing on the face of the base with its lower edge detachably secured to the base and with its upper edge extending around the upper edge of the base to the back 40 thereof, a rigid binding strip detachably secured to the upper edge of the sheet overlying the back of the base, a plurality of longitudinally adjustable screw connectors detachably secured to said binding strip and extending in parallelism from the binding strip 45 to points therebelow on the back of the base and operable to draw the upper edge of the sheet toward the lower edge thereof thereby to maintain the sheet taut and snugly fitted 50 against the face of the base.

3. A hand card comprising a base having 55 parallel upper and lower edges, a handle projecting from the back of the base, a flexible sheet of card clothing on the face of the base, a plurality of longitudinally adjustable connectors at the back of the base for drawing together relatively the upper and lower edges of the sheet thereby to maintain the sheet taut and snugly fitted against the face of the 60 base, and means projecting from the back of the base in engagement with the said connectors acting to prevent lateral movement between the connectors and the base and consequently between the sheet and the base.

65 4. A hand card comprising a metal base

having a backwardly curved, straight upper edge and a parallel lower edge, a handle projecting from the back of the base, a flexible sheet of card clothing on the face of the base with its upper edge extending around the upper edge of the base to the back thereof, a rigid binding strip engaging the lower edge of said sheet, means for detachably clamping the lower edge of the sheet between said lower binding strip and the lower edge 70 of the base, a rigid binding strip detachably secured to the upper edge of the sheet at the back of the base, and adjustable connecting means mounted on the back of the base detachably engaging the upper binding strip, 75 operable to draw the upper edge of the sheet toward the lower edge thereof thereby to maintain the sheet taut and snugly fitted against the face of the base.

5. A hand card having the construction 80 defined in claim 3, in which threaded studs pass through the upper rigid binding strip and the flexible sheet of card clothing and the screw connectors form nuts threaded on the studs and therewith clamping the binding strip and sheet together.

6. A hand card comprising a metal base 85 having a straight, rounded upper edge presenting a sharply defined shoulder at the back of the base facing the lower edge, a handle projecting from the back of the base, a flexible sheet of card clothing on the face of the base detachably secured to the base at the lower edge and extending around the upper edge of the back of the base, a metal strip secured to the upper edge of the card clothing on the face adjacent the base and adapted to engage the aforesaid shoulder when the upper edge of the card clothing is bent around the upper edge of the base and thus to stretch the card clothing taut against the face of the base and adjustable means for securing the upper edge of the card clothing, when thus stretched, in place at the back of the base.

7. A hand card comprising the construction 100 defined in claim 6, in which the said securing means comprises a plurality of longitudinally adjustable screw connectors extending in parallelism from the binding strip to points therebelow on the back of the base and operable to draw the upper edge of the sheet of card clothing toward the lower edge.

8. A hand card comprising a metal base 105 having a straight, rounded upper edge, presenting a sharply defined shoulder at the back of the base facing the lower edge, a handle projecting from the back of the base, a flexible sheet of card clothing on the face of the base detachably secured to the base at the lower edge and extending around the upper edge to the back of the base, a pair of metal clamping strips engaging the opposite faces 120 of the upper edge of the card clothing, screws passing through said strips and card cloth- 125

ing, a plurality of longitudinally adjustable screw connectors threaded respectively to the screws passing through the clamping strips and constituting nuts therefor, the metal clamping strip on the face of the sheet of card clothing adjacent the base adapted to engage the aforesaid shoulder when the upper edge of the card clothing is bent around the upper edge of the base and thus to stretch the said card clothing taut against the face of the base, the said screw connectors extending in parallelism from the binding strips to points therebelow on the back of the base and acting to secure the upper edge of the card clothing, when stretched over the said shoulder, in place at the back of the base and operable further to draw the upper edge of the card clothing toward the lower edge.

In testimony whereof, I have signed my name to this specification.

JOHN GODFREY GOURDEAU.
